[57] CLAIM

The ornamental design for a combined dinosaur toy and container, as shown and described.

DESCRIPTION

FIG. 1 is an exploded perspective view of a combined dinosaur toy and container showing my new design;
FIG. 2 is a front elevational view of the dinosaur, shown broken away for ease of illustration;
FIG. 3 is a left side elevational view of the dinosaur, the opposite side being a mirror image;
FIG. 4 is a rear elevational view of the dinosaur;
FIG. 5 is a top plan view of the dinosaur;
FIG. 6 is a bottom plan view of the dinosaur;
FIG. 7 is a front elevational view of the container, shown broken away for ease of illustration;
FIG. 8 is a left side elevational view of the container, the opposite side being a mirror image;
FIG. 9 is a top plan view of the container;
FIG. 10 is a bottom plan view of the container;
FIG. 11 is an elevational view of the inside of the top and bottom portions of the container; and,
FIG. 12 is a perspective view of the container, shown closed.
FIGS. 2-6 are shown on an enlarged scale.
